(57) **CLAIM**

The ornamental design for an electronic cigarette, as shown and described.

DESCRIPTION

FIG. 1 is a perspective view of an electronic cigarette, with a transparent tapered end portion of the mouthpiece;
FIG. 2 is a front view of the electronic cigarette, with a transparent tapered end portion of the mouthpiece;
FIG. 3 is a rear view of the electronic cigarette, with a transparent tapered end portion of the mouthpiece;
FIG. 4 is a left side view of the electronic cigarette, with a transparent tapered end portion of the mouthpiece;
FIG. 5 is a right side view of the electronic cigarette, with a transparent tapered end portion of the mouthpiece;
FIG. 6 is a top view of the electronic cigarette, with a transparent tapered end portion of the mouthpiece; and,
FIG. 7 is a bottom view of the electronic cigarette, with a transparent tapered end portion of the mouthpiece.
The evenly spaced broken lines in the drawings depict portions of the electronic cigarette that form no part of the claimed design; the dash-dot-dash line represents a boundary of the claimed design.
